CLAIM

The ornamental design for a pad for tire protectant applicator, as shown and described.

DESCRIPTION

FIG. 1 is a perspective view of the pad for tire protectant applicator, and a gripping handle in broken line to create context and background, but the handle is not part of the invention.

FIG. 2 is a first end view of the pad.

FIG. 3 is a side view of the pad.

FIG. 4 is a second end view of the pad.

FIG. 5 is a bottom view of the pad; and,
FIG. 6 is a top view of the pad.
